CUSHIONING MEANS FOR DRAFT GEARS
AND THE LIKE

Lloyd B. Jones, Hollidaysburg, Pa., assignor to The Pennsylvania Railroad Company, Philadelphia, Pa., a corporation of Pennsylvania

Original application September 27, 1941, Serial No. 412,615, now Patent No. 2,322,642, dated June 22, 1943. Divided and this application March 4, 1943, Serial No. 477,948

3 Claims. (Cl. 213—49)

1

This invention relates to cushioning means useful more particularly in connection with the draft gears of railway cars, the present application being a division of a copending application, Serial No. 412,615, filed by me on September 27, 1941, which application issued as Patent Number 2,322,642 on June 22, 1943.

My invention has for its chief aims to effectively prevent the transmission of high-frequency vibrations, originating in draft gears, to the car bodies, and to attain this objective with absence of objectionable grating noises such as ordinarily attend the operation of draft gears.

Another aim of my invention is to secure the above advantages in a compact self-contained cushioning unit which can be substituted in standard draft gears in place of the usual types, without necessitating any changes whatever in the construction of the draft gears or interfering with their normal mode of operation; and in which the shocks are absorbed by resilient elements of rubber or the like acting in compression as well as in shear when subjected to load. Thus, advantage is taken of the well known characteristics of rubber which has superior work absorption qualities in shear as compared with pure compression.

How the foregoing and other objects and important advantages can be readily realized in practice will appear from the following description of the attached drawing, wherein

Fig. 1 is a fragmentary view in horizontal section of a conventional railway car draft gear in which a pair of my improved cushioning units is incorporated.

Fig. 2 is a cross section of the organization taken as indicated by the angled arrows II—II in Fig. 1.

Fig. 3 is a fragmentary detail view corresponding to Fig. 1 drawn to a larger scale.

Figs. 4, 5 and 6 are perspective views of certain of the component parts of one of the cushioning units.

In Figs. 1 and 2 of these illustrations, the usual laterally spaced side channels of the center sill of a standard form of railway car are indicated at 10 and 11, the yoked draw bar of the draft gear at 12, and the draft stop castings at 13 and 14, the latter being rigidly secured to the inner faces respectively of said sill channels either by riveting or welding.

The cushioning units of my invention, each designated comprehensively by the reference character 15 in Figs. 1 and 2, are proportioned to fit into the transversely aligned pocket recesses

16, 17 respectively of the draft stop castings 13 and 14 generally in the same manner as the metallic spring type buffer units heretofore ordinarily employed. As shown, each cushioning unit 15 includes a multiplicity of rigid T-section pressure bars 18 of which the tongues have their opposite side faces roughened or corrugated as best seen in Figs. 3 and 4, said bars being preferably of metal and arranged in pairs of opposing rows or groups with the tongues of the bars of one group extending into clearance intervals between the head flanges of the bars of the other group. Lodged between the tongues of adjacent reversely positioned pressure bars 18 of the opposing groups are smooth-surfaced plain section elongate resilient bars or slabs 19 of rubber or the like, one of which latter is separately illustrated in perspective in Fig. 5, said bars 19, having their opposite longitudinal edges abutting the shoulders 20 afforded by the head flanges of such adjacent pressure bars. From Fig. 1 it will be seen that a rigid separator plate 20, preferably of metal, is interposed between each row of opposing pressure bars 18 and associated resilient slabs 19 and that the whole pack is snugly enclosed in a tubular housing element 21 (Fig. 6) which is rectangular in cross section and aligned in the direction of draft. The casing member 21 is closed at the opposite ends by cover plates 22 and 23, which, like the separator plates 20, are capable of free movement within said housing. The cushioning units 15 can be withdrawn downwardly, together with the draw bar 12, from between the draft stop castings 13 and 14 upon removal of the usual retaining plate 25 which is bolted to the bottom flanges of the center sill channels 10 and 11. As shown each housing element 21 is disposed in an opening of the yoke bar 12 and has its protruding side portions fitting between the shoulders of opposite recesses 16 in the stop castings 13.

With the parts constructed and arranged as described, it will be seen that as pull is induced in the draw bar 12, for example from the left in Fig. 1, the housing cover plates 23 of the two serially positioned cushioning units 15 will be obliged to follow suit. This movement will be yieldingly resisted through coaction of the opposing pressure bars 18 of the several layers with the respectively associated resilient slabs 19, and the shock progressively transmitted from one layer to the next in each unit through the medium of the separator plates 20 until it is finally absorbed. On the other hand, when the draw bar 12 is drawn to the right in Fig. 1, the movement will be gradually absorbed in a like manner, through

initial movement of the housing cover plates 22 of the two units, and communicated progressively to the resilient slabs 19 in the several layers by the rigid bars 18 likewise through the medium of the separator plates 20. Due to enforced lateral expansion incident to being compressed, the resilient slabs 19 are gripped by the roughened side faces of the tongues of adjacent opposed rigid bars 18 in the several rows and placed in shear, the resistance offered varying proportionately to the degree of pressure imposed. The cushioning units 15 will thus operate silently in preventing the transmission to the car body of sudden shocks and noises caused by spasmodic movements of the draft gear.

While I have herein shown the bars 18 and 19 as being vertically arranged, they may, if desired or found more convenient in practice be horizontally placed without sacrifice of any of the advantages hereinbefore pointed out.

Having thus described my invention, I claim:

1. Cushioning means for use in a draft gear having a yoked draft bar and pairs of longitudinally spaced stop shoulders arranged along opposite sides of the draft bar in fixed relation to the underframe of the car, said cushioning means comprising a tubular housing element aligned in the direction of draft and disposed within the yoke opening in the draft bar with the projecting side portions thereof fitting into the intervals between the respective pairs of stop shoulders and thereby held against movement in the assembly; cover plates slidable within and closing the opposite ends of the housing element and adapted to be abutted by the opposite end surfaces of the

5 yoke opening in the draft bar; and resilient means comprising a plurality of compacted, compressible and intervening rigid elements which are separable both longitudinally and transversely of the center sill interposed between said end plates within the housing to maintain said plates yieldingly in engagement normally with the respective stop shoulders of the respective pairs.

2. The invention according to claim 1, wherein the resilient means includes groups of opposingly-arranged rigid pressure bars of T cross section having tongues with roughened side faces, the tongues of one group extending into clearance intervals between the head flanges of the bars of the other group; and elongate slabs of rubber or the like individually positioned between the tongues of adjacent pressure bars of the two groups with their longitudinal edges overlapped by the head flanges of the adjacent bars and with their side faces contacting the contiguous side faces of the tongues of such adjacent bars.

3. The invention according to claim 1, wherein the resilient means includes a transverse row of vertically-positioned opposingly-arranged groups of rigid pressure bars of T cross section having tongues with roughened sides, the tongues of one group extending into clearance intervals between the head flanges of the bars of the other group; and elongate slabs of rubber or the like positioned between the tongues of adjacent bars of the two groups with their longitudinal edges overlapped respectively by the head flanges of the adjacent bars and with their side faces contacting the contiguous side faces of such bars.

LLOYD B. JONES.
